RUFUS SPAULDING MERRILL AND WILLIAM CARLETON, OF BOSTON, MASSACHUSETTS.

Letters Patent No. 73,912, dated January 28, 1868.

IMPROVEMENT IN LAMPS.

The Schedule referred to in these Letters Patent and making part of the same.

TO WHOM IT MAY CONCERN:

Be it known that we, RUFUS S. MERRILL and WILLIAM CARLETON, of Boston, in the county of Suffolk, and State of Massachusetts, have invented certain new and useful Improvements in Lamp-Burners; and we hereby declare the following to be a full, clear, and exact description of the same, reference being had to the accompanying drawings, in which—

Figure 1 is a vertical central section of a burner constructed in accordance with our invention.

Figure 2 is a like section of the same on the line *x y*, fig. 1.

Figure 3 is an elevation of the removable cone and chimney-holder, detached from the other portion of the burner.

This invention relates to that class of burners having the cone and chimney-holder mounted upon a sleeve, which fits or slides upon the wick-tube, the object of such construction being not only to isolate the base of the burner from those parts which are contiguous to or in the immediate neighborhood of the flame, but also to admit of the latter parts being readily removed from the wick-tube, so as to uncover the wick whenever it is required to trim or to light the same. In applications now pending before the United States Patent Office, in the names of R. S. MERRILL, and R. S. MERRILL and WILLIAM CARLETON, the advantages of such construction are fully pointed out and explained, and need not be here repeated.

In the accompanying drawings, the base, *A*, of the burner, which fits over the orifice in the top of the fluid-receptacle or reservoir of the hydrocarbon-fluid lamp, carries, as usual, the wick-tube *B* and rack *C*, for elevating or lowering the wick. The base is covered by a cap, *D*, which shuts in and encloses the rack *C*, and orifices in the wick-tube and base, so as to exclude all danger of explosion which would arise if the vapor of the volatile fluid which exudes from the orifices in the wick-tube, and gathers in the base, were free to communicate with the flame. The wick-tube *B* extends some distance above the cap, and has fitted upon it a sleeve, *a*, to which are attached, by suitable means, (in this instance by means of the gauze or perforated plate *b*,) the chimney-rest and holder *c*, and the cone or deflector *d*. The sleeve is capable of sliding up and down upon the tube, so that it, together with the chimney-holder and cone which it carries, can be removed from or fitted upon the said tube with perfect facility.

When the wick is lighted, in order to replace the sleeve and the parts it carries (which have been previously removed in order to light the wick) upon the wick-tube, without danger of extinguishing the flame, openings or perforations *e* are formed in the sides of the sleeve, through which, while the sleeve is being slipped down over the wick-tube, the flame receives a sufficient supply of air to keep it alive until the sleeve has reached its proper position and ceases to encircle the flame.

The combination of the sleeve and upper part of the burner with the base and wick-tube, as well as the peculiar construction of the sleeve itself, are the subjects of applications, which, as above mentioned, are now pending in the United States Patent Office. The improvement which it is now desired to secure by Letters Patent has reference to the construction of what may be termed the upper or removable section of the burner, consisting of the sleeve and parts which it carries, the object being to better adapt such section for common and every-day use.

In this portion of the burner, as heretofore made, the metal diaphragm or gauze, which closes the bottom of the cone and chimney-rest, has been given a concavo-convex form, the convexity being upon the exterior surface of the plate or gauze; and not only this, but the lower end of the sleeve has extended down some distance below the base of the chimney-rest, so that when the section is removed from the tube, and placed upon the table or other place where the lamp happens to be, it cannot be set down in an upright position without great danger of falling over, and thus breaking the chimney, which is held in the chimney-rest; for, resting, as it does, upon the narrow and contracted base formed by the bottom of the sleeve, any slight jar will suffice to destroy its equilibrium, while, if the base of the sleeve is made flush with the gauze or diaphragm, the rounded surface of the latter forbids the possibility of the section occupying an upright position, but it must be placed upon its side, in which position it is very liable to roll from the table or other place where it lies.

The object of the present invention is to so construct the section as to give it a broad base, upon which it

may stand securely when detached or removed from the burner. To this end, as shown in the drawings, the gauze or perforated plate *b*, which extends over the bottom of the section, is made concave on its under side, so that the point of its greatest depression shall be where it joins with the annular chimney-holder *c*; or, if preferred, the diaphragm may have a plane surface, flush with the bottom of the chimney-holder. In either case, however, the lower end of the sleeve *a* should not extend below the bottom of the chimney-holder, but ought, as shown in the drawing, to stop a little short of the plane in which the base of the said annular holder lies. When a section thus constructed is removed from the burner, and set down upon a table or other suitable place, it will be seen that, as represented in fig. 3, the section will stand upon the broad base formed by the annular chimney-holder, and will thus be maintained steadily in an upright position. The position upon the wick-tube of the sleeve *a*, and parts *b c d* which it carries, is shown in figs. 1 and 2. The metal diaphragm, or perforated plate *b*, is soldered or otherwise suitably secured both to the sleeve *a* and to the chimney-holder *c*, and serves to maintain the sleeve and the cone and chimney-holder in their proper relations to each other. The lower end of the sleeve rests on the cap *D*, which is of sufficient height to hold the sleeve and parts which it carries at the proper distance above the base of the burner, so as to remove the latter from the immediate neighborhood of the chimney-holder and other parts liable to become highly heated by the flame.

Having now described our invention, and the manner in which the same is or may be carried into effect, we will state our claim, as follows:

In a lamp-burner in which the cone and chimney-holder are connected with a sleeve fitting the wick-tube, we claim the arrangement of the parts, substantially in the manner herein described, so that the removable parts of the burner, when taken from the wick-tube, may be deposited in an upright position, and supported upon a broad base, as and for the purposes set forth.

In testimony whereof, we have signed our names to this specification before two subscribing witnesses.

RUFUS SPAULDING MERRILL,
WILLIAM CARLETON.
